UNITED STATES PATENT OFFICE

ACE W. SLAGHT, OF NEAR SAN JOSE, CALIFORNIA

RADIOSIGNALING

Application filed May 8, 1928. Serial No. 276,027.

This invention relates particularly to radio receiving systems.

It is one object of the invention to provide means for securing increased volume in a 5 radio receiving set.

It is another object of the invention to provide a means of the character indicated that will obviate the necessity of providing an aerial for the receiving set.

10 It is also an object of the invention to provide a means of the character indicated that will greatly increase the selectivity of the set, and greatly increase its efficiency in tuning in distant sending stations.

15 It is still another object of the invention to provide a container in which all the necessary additional elements are arranged and positioned ready for connecting as desired to a receiving set.

20 In addition to the foregoing this invention comprehends improvements in the details of construction and arrangement of parts to be hereinafter set forth and particularly pointed out in the appended claims.

25 In the drawing:

Figure 1 is a schematic diagram showing one form of my invention as applied to a four tube receiving set and a "B" eliminator.

20 Figure 2 is a diagram showing a simple 30 form of my invention independently of the receiving set.

Figure 3 is a perspective view of a receptacle with the several parts of the invention mounted therein.

35 Referring now more particularly to the drawing, I show at 1 a schematic diagram of a four tube receiving set with the aerial and ground terminals indicated at 2 and 3 respectively, the cable connector being shown in part at 4, the wires leading to the power tube, the detector tube of the set being indicated at 5 and 6 respectively, and the ninety volt "B" battery terminal of the set being indicated at 7.

40 In effecting my invention I first provide a pair of impedance coils as 8 and 9, one end of one coil as 8 being adapted to connect to the aerial binding post 2 of the set and the other end being turned back through the center of the coil as at 10 and connected to

the corresponding end 11 of the coil 9. The other end of the coil 9 is adapted to connect to the ground binding post 3 of the set as shown. A short ground 12 is inserted in the wire between the ends 10 and 11 as shown. 55 Other suitable devices may be inserted in this device as desired such as a condenser in the ground connection as shown at 13 in Figure 2.

I have found that by means of a hook-up 60 of this kind the necessity of providing either an outside or inside aerial is entirely eliminated, and that not only is the selectivity of the set greatly increased, but the volume of sound secured is greatly augmented and the 65 range of the set insofar as station distance is concerned is greatly increased. I have found that Number twenty wire wound on a one and one-half by four and one-half inch tube secures the desired results, and that this 70 device functions in the manner set forth on any tube set to which it may be connected.

The results obtained by the device as described are greatly enhanced when the set is used in conjunction with a "B" battery eliminator by making the following insertions in the hook-up. In the wire 16 connecting the power tube terminal 14 of the "B" eliminator 15 with the power tube terminal 5 of the set I insert an impedance coil 17, the end of the 75 coil connecting with the eliminator portion of the wire 16 passing through the coil as shown. In the wire 18 connecting the ninety volt terminal 7 on the set with the ninety volt terminal 19 on the eliminator I insert an impedance coil 20, the end of the coil connecting with the eliminator portion of the wire 18 passing through the coil as shown. In the wire 21 connecting the detector tube terminal 22 on the eliminator with the detector tube terminal 6 of the set I insert a suitable filter as 23. These insertions still further increase the range of usefulness of the set and may be connected to the set in various ways, and to various sets according to their 85 schematic diagrams.

I provide these several devices ready for use in the following manner. First I provide a suitable insulating jar of glass as 24 having a plurality of compartments as 25, 26, 27, 28, 29 90

and 30 formed therein. In each of these compartments I imbed one of the devices in white paraffin wax with their ends exposed for making the desired connections.

5 As many changes could be made in the foregoing described construction and arrangement and many apparently widely different embodiments of this invention could be made without departing from the scope thereof,
10 it is intended that all matter contained in the above description or shown in the accompanying drawings shall be interpreted as illustrative and not in a limiting sense. It is also to be understood that the language
15 used in the following claim is intended to cover all of the generic and specific features of the invention herein described.

I claim:

20 In a radio receiver, a radiant energy collector unit comprising a pair of permanently fixed coils having a predetermined fixed spaced relation, one of said coils having one of its ends connected to the ground terminal of the receiver and its opposite end connected
25 to a conductor extending axially through said coil and connected to ground, the other of said coils having one of its ends connected to the aerial terminal of the receiver and its opposite end connected to a conductor extending
30 axially through the last named coil and connected to the said ground.

ACE W. SLAGHT.
